UNITED STATES PATENT OFFICE

2,084,170

SASH CONSTRUCTION

Christian M. Verhagen, Chicago, Ill., assignor
to The Adlake Company, Chicago, Ill., a cor-
poration of Illinois

Application June 6, 1935, Serial No. 25,269

7 Claims. (Cl. 189—76)

This invention has to do with vertically slide-
able sash of the type used in the windows of
railway cars, busses and other vehicles, and is
particularly concerned with the way in which
5 the bottom rail sealing strip is held in place.

The usual practice has been to provide a chan-
nel with inturned side flanges on the lower edge
of the bottom rail and fit into it a rubber strip
with undercut side grooves, relying upon the en-
10 gagement of the flanges within the grooves to
keep the strip in position. The trouble with this
sort of mounting has been that at the ends of
the bottom rail where the rubber strip projects
15 into the guides there is a pull on the ends of the
strip when raising the sash in closely fitting
guides, which pull frequently is enough to start
one of the ends of the strip out of the channel,
and when this once begins the strip will peel out
20 with but very little resistance. This difficulty
is particularly pronounced where the sash is of
the type in which a rubber or felt strip is mount-
ed in or on the side rail for engagement with the
guide, in which case the projection of such side
25 rail strip beyond the end of the bottom rail
proper leaves the underlying end portion of the
bottom rail sealing strip without any supporting
means.

The present invention resides in the provision
of a simple but very practical device, in the form
30 of a corner clip, which will entirely overcome this
difficulty without requiring any changes and
without adding appreciably to the cost of the
sash.

While the foregoing statements are indicative
35 of the nature of the invention, other objects and
advantages will be apparent to those skilled in
the art upon a full understanding of the con-
struction and function of this new device.

Two slightly different embodiments of the in-
40 vention are herein illustrated and described, but
it will of course be appreciated that the invention
is susceptible of incorporation in still other
structurally modified forms coming equally within
the scope of the appended claims.

45 In the accompanying drawings:

Fig. 1 is an inside face view of one of the lower
corners of a vertically slideable metal sash, with
the end of the sealing strip on the bottom rail of
the sash clamped in place in accordance with the
50 invention;

Fig. 2 is an edge view of the sash structure
shown in Fig. 1;

Fig. 3 is a vertical section through the sash,
taken on the line 3—3 of Fig. 2;

55 Fig. 4 is a vertical section through the bottom

rail and sealing strip, taken on the line 4—4 of
Fig. 3;

Fig. 5 is a horizontal section through the side
rail, taken on the line 5—5 of Fig. 3;

Fig. 6 is a perspective view of the corner clip 5
used in securing the extreme projecting end of
the bottom rail sealing strip; and

Figs. 7 to 12 inclusive are views corresponding
respectively to Figs. 1 to 6 inclusive, showing a
somewhat different embodiment of the invention. 10

The sash which is illustrated fragmentarily
in Fig. 1 has a sheet metal bottom rail 10 which
contains a channel 11 in its lower edge for the
reception of a soft rubber sealing strip 12. As is
customary in sash structures of this type, the 15
side walls of the channel 11 are provided with
inturned flanges 13 which fit into undercut
grooves 14 in the sides of the strip. The strip
13 is inserted in the channel 11 either by feed-
ing it endwise into the same or else by tilting the 20
strip to get one side in and then forcing the other
side in with a suitable tool.

The bottom rail 10 is connected by a corner
insert 15 to a side rail 16, which side rail, in the
particular sash structure shown, is equipped with 25
a special side rail extension in the form of a soft
rubber strip 17, in accordance with the teaching
of Hamm Patent No. 1,981,355. The strip 17 is
secured within a channel in the edge of the side
rail 16 in much the same manner as the strip 12, 30
with the lower end of the strip 17 overlying the
unsupported end 18 of the strip 12 some little dis-
tance beyond the end of the bottom rail 10.

Behind the rubber strips 12 and 17 an L-shaped
35 sheet metal member 20 is secured about the sheet
metal portions of the corner of the sash against
the mitered ends of the bottom and side rails,
being held in position by certain of the screws
21 used to fasten the insert 15 within the ends
of the rails. The member 20, which is in the 40
form of a narrow strip, coacts with the insert 15
to hold the mitered ends of the rail snugly to-
gether, in accordance with the teaching found
in the recently allowed application of William
S. Hamm and Harry D. Severson, Serial No. 698,032. 45

In carrying out the present invention, a tongue
22 may be cut out of the center of the upwardly
extending portion of the strip 20 and projected
outwardly and downwardly and caused to termi-
nate in a reversely bent horizontally extending 50
clip portion 23. This projecting clip 23 extends
into a recess 24 near the end of the bottom rail
sealing strip 12 beneath the lower end of the strip
17 and by engaging with the upper surface of
the recess in a more or less resiliently clamped 55

association serves to hold the extreme end of the strip 12 snugly in position against the bottom of the strip 17 and prevent the end of the strip 12 from being pulled out of position by reason of 5 its frictional engagement with the side walls of the guide.

While the clip 23 is shown as a part of the corner member 20, it will of course be understood that it may be made as a separate part and that 10 it is in no way dependent in the performance of its function on the presence of the corner member, the latter being used or not, as desired. Likewise, the herein disclosed feature of clamping up the end of the bottom rail sealing strip is 15 obviously not limited in its application to those sash structures which have side rail extension strips, as the retention of the sealing strip is of importance in other types of sash.

The retaining clip 23, in addition to keeping 20 the end of the sealing strip from being pulled out of its channel in the bottom rail, will prevent the strip from working endwise in either direction, it being of course understood that it is desirable to use two clips to a sash, one at each end of 25 the bottom rail.

In the embodiment which is shown in Figs. 7 to 12 inclusive, a type of sash structure is illustrated wherein no outside corner strap is used. In this case the retaining clip 25 may advantageously be 30 formed on the lower end of a downwardly extending lip 26 on a sheet metal guideway 27 provided for the latching bolt. In this embodiment it will be noted that the horizontally extending portion of the clip 25 projects into a slit which is 35 provided for its reception in the upper or head portion of the sealing strip, rather than into the hollowed out lower portion of the strip. As illustrative of the adaptability of this improvement to sash structures of various kinds, it will 40 further be noted that the side rail 30 of the sash shown in connection with this embodiment is provided with a rib 31 on which a felt covered metallic channel member 32 is fastened for co-action with the usual guide, in accordance with 45 the teaching in Hamm and Sevison Patent No. 1,997,822.

I claim:

1. The combination, with the bottom rail of 50 a sash having a channel with inturned side flanges, and a rubber sealing strip in the channel having undercut side grooves for the reception of the flanges, of a clip at the end of the bottom rail which enters a recess in the end of the sealing strip and bears upwardly 55 against the upper surface of the recess.

2. The combination, with the bottom rail of a sash having a channel with undercut side flanges, and a rubber sealing strip in the channel having undercut side grooves for the reception of the flanges, of a clip at the end of the bottom rail which projects downwardly and terminates in a horizontally disposed portion which enters a recess in the end of the sealing strip and bears upwardly against the upper surface of the recess. 5

3. The combination, with the side rail of a 10 sash having a projecting non-metallic guide-engaging member, a bottom rail terminating short of said projecting member, and a rubber sealing strip at the lower edge of the bottom rail projecting beyond the latter flush with said member, of means carried by the sash beneath the end of the bottom rail sealing strip for preventing the latter from being pulled away from the overlying lower end of the non-metallic side rail member by the friction of the guides. 15 20

4. A sash provided with a bottom rail, a rubber sealing strip in engagement with the bottom rail, means coextensive with the rail for holding the strip against the rail, and other means extending beyond the rail ends and engaging the 25 strip for preventing the ends from being pulled downwardly.

5. A sash provided with a bottom rail having a longitudinally extending channel therein, a rubber sealing strip in the channel and projecting beyond the ends thereof, means in engagement with the strip for holding the latter in the channel, and other means hooked under the projecting ends of the strip for preventing the ends from being pulled downwardly. 30 35

6. A sash provided with a bottom rail having a longitudinally extending channel therein, a rubber sealing strip in the channel and terminally extending beyond the ends thereof, means extending the full length of the bottom rail in 40 engagement with the strip for holding the latter in the channel, and other means at the ends only of the strip in engagement with downwardly facing surfaces of the latter for preventing the ends from being pulled downwardly. 45

7. A sash provided with a bottom rail having a longitudinally extending channel therein, a rubber sealing strip in the channel with the ends of the strip projecting beyond the ends of the rail, means extending the full length of the rail 50 in engagement with the strip for holding the latter in the channel, and other means at the projecting ends only of the strip for preventing such ends from being pulled downwardly. 55

CHRISTIAN M. VERHAGEN.
